UNITED STATES PATENT OFFICE.

STEPHEN S. THOMAS, OF ALEXANDRIA, LOUISIANA.

STOVE OR THE LIKE.

Application filed March 17, 1922. Serial No. 544,694.

To all whom it may concern:

Be it known that I, STEPHEN S. THOMAS, a citizen of the United States, residing at Alexandria, in the Parish of Rapides and State of Louisiana, formerly residing at Peebles, in the county of Adams and State of Ohio, have invented certain new and useful Improvements in Stoves or the like, of which the following is a specification.

The present invention has to do with certain improvements in stoves or heaters, and more particularly the said invention has to do with improvements in stoves which are provided with coverings of heat-insulating material to thereby better retain the heat within the interior of the stove. More particularly the invention relates to a device of this kind in which the interior of the stove may be initially heated by the generation of heat on the interior of the stove, the said heat being conserved by the heat-insulating material, so that after the desired temperature has been attained the subsequent operation may be conducted simply by the use of the heat so generated and retained on the interior of the device.

There have been in the past devised a number of stoves or heaters operating on the general principle mentioned above. However, it has been found very difficult and in many cases impossible to secure a uniform heating action in all portions of the stove. This has resulted, among other things, by reason of the fact that the heating gases are not properly distributed with respect to the different portions of the oven structure. It is well understood that there is ordinarily a tendency for the greatest heat to concentrate in the rear or back portion of the oven, so that articles placed in the rear portion will frequently become burned or overcooked before articles in the front portion of the oven are properly cooked. One of the objects of the present invention is to provide a construction by means of which a very uniform heating action may be secured throughout the entire oven body.

Another feature of the present invention has to do with the provision of a construction which will be very well adapted for heating by means of different kinds of fuel, such as gasoline, kerosene, gas, and other fuels. It is well understood that the products of combustion of some fuels are much heavier than the products resulting from the

combustion of other fuels. In fact, the products of combustion of some fuels are heavier than air, whereas the products from the combustion of other fuels are lighter than air. A stove which will operate properly with one kind of fuel will not necessarily operate properly with another kind of fuel, because of this difference in the weight or specific gravity of the products of combustion. This is particularly true where the movement of the hot gases or products of combustion is occasioned solely by natural draft. The hot products of combustion from one fuel may circulate properly through the heating passages, whereas the products of combustion from another fuel may not circulate at all on account of the difference in weight or specific gravity of the two classes of products of combustion.

Another feature of the present invention has to do with the provision of an arrangement whereby the circulation of the products of combustion through the heating flues may be modified or changed according to the kind of fuel which is being consumed, so that a proper circulation of the heating gases may be secured at all times, regardless of what kind of fuel is being used.

Another feature of the invention has to do with the mechanical construction of the stove, and the main object of this feature is to provide a construction such that the device may be manufactured in a very simple manner from blanks or sheets of metal which may be cut or stamped out and assembled in a very simple manner and at comparatively low expense.

Other features and objects of the invention will appear from a detailed description of the same, which consists in the features of construction and combinations of parts hereinafter described and claimed.

Referring to the several drawings:

Figure 1 shows a perspective view of the oven, with certain portions thereof and portions of the heat insulation broken away;

Fig. 2 shows a vertical section taken on line 2—2 of Fig. 1, looking in the direction of the arrows;

Fig. 3 shows a vertical cross section taken on line 3—3 of Fig. 2, looking in the direction of the arrows; and

Fig. 4 shows a horizontal section taken on line 4—4 of Fig. 3, looking in the direction of the arrows. Fig. 4 may also be

considered as being taken on line 4—4 of Fig. 2, looking in the direction of the arrows; and

Fig. 5 shows a broken horizontal section 5 on line 5—5 of Fig. 3 looking in the direction of the arrows.

In the construction shown in the several figures, there is provided a closed oven located above a broiling oven, wherein the 10 gas or other fuel is burned for the generation of the hot gases which serve to heat the closed oven. I desire to state at this point, however, that the features of my invention are in nowise limited to use in conjunction with a broiling oven associated 15 with a single closed oven.

The closed oven is designated by the number 12. It comprises the side walls 13 and 14, the bottom 15, the top 16, and the back 20 17 in conjunction with the door 18. The side walls 13 and 14, the bottom 15 and top 16 are conveniently formed from a single sheet of metal bent into the form indicated in Fig. 3, and having its end portions 25 lock-jointed together, as shown at 19. The back sheet 17 is locked to the back periphery of the sheet just described. The front periphery of the sheet, which forms the sides, top and bottom of the oven, is flanged 30 outwardly, as shown at 20, for a purpose to be presently explained. Suitable ledges 21 may be formed in the side walls of the oven, by indenting or corrugating said walls, said ledges serving to support pans 35 or trays in the usual manner.

Encircling the sides and top of the oven is an inverted U-shaped plate, which provides the side walls 22 and 23 and the top 24. This plate is of sufficient size, and is so located as to provide passages 25 and 26 adjacent to the side walls of the oven, and passages 27 and 28 above the top 16 of the oven. A back plate 29 is lock-jointed to the rear edge of the top portion 24 of the U-shaped plate, and the side edges of the back plate 29 are jointed to the rear edges of the side walls 22 and 23 of the U-shaped plate. The front edges 30 and 31 of the side walls 22 and 23 are flanged outwardly, 50 as shown in Fig. 4, for a purpose to be presently explained. A bottom plate 32 has its front edge 33 bent downwardly for a purpose to be presently explained. The side edges 34 and 35 of this bottom plate 55 are so bent as to provide upwardly facing sockets for the reception of the lower edges of the side walls 22 and 23, respectively, as is clearly shown in Fig. 3. The lower edge 36 of the back plate 29 is so bent as to 60 provide a forwardly facing socket for the accommodation of the rear edge of the bottom plate 32, in the manner clearly indicated in Fig. 2.

A burner 37 of suitable form and construction is mounted in the upper portion

of the broiling oven and beneath the closed oven. In the particular construction illustrated this burner is adapted to the burning of gas delivered through the pipe 38, but it will be readily appreciated that any other 70 suitable burner adapted to the combustion of any other suitable fuel may be used. A false bottom 39 is located between the burner and the bottom plate 15 of the oven, said false bottom serving to prevent a direct 75 impingement of the hot gases from the burner against the bottom of the oven, and causing said gases to pass to both sides of the oven and upwardly adjacent to the said sides. These hot gases pass upwardly 80 through the passages 25 and 26 into the passages 27 and 28 located above the top of the oven. The gases collecting at the top of the oven from the passages 27 and 28 may be disposed of either directly 85 through a flue 40, which communicates with the forward ends of said passages, said flue leading rearwardly to a suitable discharge point, or the said gases may be disposed of by leading them downwardly adjacent to 90 the forward portions of the side walls of the oven in the manner to be presently explained.

It will be observed that the port 41 which connects the flue 40 with the passages 27 and 28 is located well forwardly with respect to the top of the oven, so that the gases, in order to reach the flue 40 by way of the port 41, must of necessity travel adjacent to the upper forward corners of the oven. This will insure a thorough heating of the said upper forward corners of the oven, and will in considerable measure draw the hot gases away from the rear portion of the oven where they would ordinarily collect, thus insuring a uniform heating of the forward portion of the oven. This is a very important consideration, for the reason previously mentioned, that it is ordinarily difficult to properly heat the upper forward portion of the oven.

A partition 42 extends along the upper central portion of the top 16 of the oven, thereby isolating the passages 27 and 28 from each other. At the sides of the broiler 115 are located certain plates. Inasmuch as these plates are reversed duplicates of each other, it will suffice to describe a single one of them in detail. The plate comprises a lower body portion 43, having an opening 44 formed in its rear portion, some of the metal struck out from said opening being bent sidewise to provide a lip 45. The plate includes also an upper portion 46, the upper end of which is turned over to provide a 120 lip 47, which lip has its central portion cut away to provide an opening 48. The forward edge of the portion 43 is so formed 125 as to provide a hook which is adapted to co-operate with another element in the manner 130

presently to be described. The rear edge of the portion 43 is flanged outwardly as at 50. Each of the plates 43 is L-shaped, and is entirely open above the horizontal arm 5 or branch to permit communication with passages 25 and 26, respectively, at the two sides of the oven.

Referring particularly to Figs. 2 and 3, the mode of application of these side plates 10 will be readily understood. They are set into the side portions of the broiler, the upper extremities of the parts 46 being entered into the lower ends of the passages 25 and 26, respectively, as shown in Figs. 2 15 and 3. When so entered, these upper ends serve to isolate the passages 51 and 52 at the sides of the broiler, the upper ends of said passages communicating with the lower ends of the passages 25 and 26, respectively, 20 by way of openings formed by the cut-away portions 48. It therefore follows that the gases descending through the passages 25 and 26 at the sides of the oven will be delivered, respectively, into the passages 51 25 and 52 at the sides of the broiler. The rear edges of the upper portions 46 of these plates are flanged outwardly, as shown at 53, for the purpose of enclosing the rear sides of the passages 51 and 52. The front 30 sides of said passages are closed by means of the front of the stove. Angled bars 55 or the like, which are entered between the lower portions 43 and the adjacent side walls 22 and 23 serve to isolate passages 56 35 and 57 from the passages 51 and 52, respectively, so that the gases flowing downwardly through the passages 51 and 52 cannot return rearwardly to the passages 56 and 57 and thereby commence an upward 40 flow.

The bottom sheet 32 previously described is provided with openings 58, 59, 60 and 61. The openings 60 and 61 at the forward side 45 portions of said plate are flanged downwardly, as shown in Fig. 3, and enter into a cross-tube or flue 62, within which all of the products of combustion passing downwardly through the passages 51 and 52 are collected. The cross-connection 62 communicates with a rearwardly extending passage 63, whereby all of the gases within 50 said connection are delivered to an upwardly extending flue 64, which flue 64 leads to a discharge connection 65. The flue 40, which was previously described, also 55 communicates with the discharge connection 65 under the control of a damper 66, which in Fig. 2 is shown in closed position. With the damper in the position shown in Fig. 2, 60 the products of combustion are prevented from passing over the flue 40 through the discharge connection 65, and are compelled to pass downwardly by way of the passages 25 and 26, and 51 and 52, to the cross connection 62, whereby they are delivered

through the passage 63 to the flue 64. By reversing the damper 66, the products of combustion will be permitted to pass directly from the passage 40 to the discharge connection 65. It thus appears that I have provided for discharging the products of combustion, either directly upward or indirectly downward, to the discharge connection. In the first case, the products of combustion lighter than air will readily discharge, 70 and in the second case the products of combustion heavier than air will readily discharge by reason of their ability to flow downwardly by way of the passages 25, 26, 75 51 and 52.

The other openings 58 and 59, previously mentioned in the description of the bottom plate 32, are flanged outwardly, for the accommodation of the upper ends of the air supply ports 69 and 70, respectively. The 80 air entering through these ports passes upwardly and finds its way into the passages 56 and 57, and flows thence through the openings 44 into the broiling oven, where it finds its way to the burner.

An outside covering is built up for the stove in the following manner: A U-shaped plate provides the top 71 and the side walls 72 and 73. A plate 74 provides the bottom. The plate 74 is flanged into a pan shape, and a rectangular band or bar of metal 75 is seated just inside of the said flange. The lower edges of the side walls 72 and 73 are flanged upwardly around this bar of metal, thus locking the side walls and bottom sheet 85 together. A sheet 76 closes the back of the oven. The top and side edges of this sheet are flanged onto the rear edges of the top 71 and the side walls 72 and 73, as best shown in Fig. 2; and the bottom edge of the 90 back sheet is flanged upwardly onto the bar 75.

A sheet 77 provides the front of the stove, and said sheet has its top and side peripheries lock-jointed to the forward edges of the top 110 71 and the side sheets 72 and 73, as best shown in Fig. 2. The front sheet is provided with a pair of openings corresponding to the door 18 of the oven and the door 78 which leads into the broiling oven. In the 115 construction illustrated, it is necessary to provide seats for these doors, and also it is necessary to provide a space adjacent to the cross-partition 79 for the accommodation of heat-insulating material. All of these results are accomplished by the constructions 120 which I will now describe.

A plate 80 encircles the opening for the oven door 18, and a plate 81 encircles the opening for the broiler door 78. The outer 125 periphery of the plate 80 is flanged outwardly, as at 82, said flanged portion seating against a depressed portion 83 of the front plate. The inner periphery 84 of the plate 80 is flanged inwardly. It was previously 130

explained that the forward periphery of the plate comprising the sides, top and bottom of the closed oven is flanged outwardly, as shown at 20 in Fig. 2. This flange 20 co-
5 operates with the flange 84 just described, in the manner shown in Fig. 2, so that the plate 80 cannot be withdrawn without a simultaneous withdrawal of the side walls, top and bottom of the oven.

10 The outer periphery of the plate 81 is flanged outwardly, as at 85, said flange seating into a depression 86 of the front plate, and the inner periphery of the plate 81 is flanged inwardly, as at 87. It was previously
15 explained that the forward edge of the bottom plate 32 is flanged downwardly, as at 33, and this flange co-operates with the flange 87 to lock the plate 32 to the plate 81, as best shown in Fig. 2. An L-shaped plate 88 extends across the stove behind the partition 79, said plate 88 having its lower edge 89 flanged against the flange 87 and lock-joined throughout, as shown in Fig. 2. The upper portion 90 of the plate 88 extends
20 forwardly and seats against the inner surface of the partition 79, as shown in Fig. 2. A pair of transverse bars 91 and 92 extend from front to rear of the stove between the bottom of the oven and the top surface of
25 the false bottom 39, the rear ends of said bars resting against the back sheet, and their front ends pressing against the L-shaped plate 88 and serving to hold the same up against the partition 79.

30 It was previously explained that the forward edges of the top sheet 24 and of the side sheets 22 and 23 are flanged outwardly. These flanged portions co-operate with the top and side portions of the plate 80, and with the side portions of the plate 81, as shown in Fig. 2, so that, upon forcing home the plates 80 and 81, a wedging action will be secured. In order to improve the wedging engagement just mentioned, it will be found
35 desirable under many circumstances to insert a strip or sheet of such material as asbestos sheeting between the metal plates. I have, therefore, illustrated a strip of asbestos 92 between the sheet 80 and the flanges
40 of the top and side sheets with which it engages, said asbestos being best shown in Fig. 2. I will presently explain how strips of asbestos or the like may also be inserted at other desirable points where metal would otherwise engage metal.

45 The doors 18 and 78 are conveniently built up in the manner shown in the several figures. The construction illustrated includes the use of sheet metal pans 93 and 94 for the
50 two doors. Each of these pans has its periphery formed or beveled at a suitable angle to engage firmly against the surface of the corresponding sheet 80 or 81, so that when the doors are closed a very snug contact will be secured. The extreme outer

periphery 95 of each of these pans is flanged outwardly, as best shown in Fig. 2, and said pans are closed by means of the outside plates 96 and 97, respectively, the peripheries of said plates being flanged over the flanges 95 of the corresponding pans. The doors thus constructed may be hinged to the front of the stove in any suitable manner, as by means of the hinges 98 and 99.

55 While it is true that a very snug fit may be secured, metal to metal, by the arrangement thus described, still in many cases this will not insure a gas-tight fit, and consequently there might be an escape or leakage of steam or other vapors from the interior portions of the stove. I have, therefore, made provision for seating the doors against yielding gaskets of asbestos or other suitable material. It was previously explained that the flange 20 co-operates with the flange 84 at a point adjacent to the door 18, and that the flanges 33 and 89 co-operate with the flanges 87 adjacent to the door 78. I have illustrated at each of these points of engagement a strip of asbestos 90 tubing or other yieldable material 100, which strip of material has its inner edge gripped between the adjacent co-acting flanges, and has its outer edge turned down into such position as to engage or contact against the inner surface of the corresponding door pan when closed. This arrangement will be readily understood by an examination of Fig. 2.

60 It is desirable to provide means for locking the doors in closed position and for forcing them home so as to insure the gas-tight sealing previously discussed. Nevertheless, it will be appreciated that in many cases it would be very dangerous to absolutely lock the doors of a device of this kind against any possibility of opening under the influence of the internal pressure. This danger exists by reason of the fact that it will sometimes happen that an explosion 100 will take place on the interior of the stove, which explosion, were it to be absolutely resisted by the doors, would result in a complete disruption of the stove structure. I have, therefore, illustrated a construction 105 whereby the doors may be locked in a sufficiently tight manner to insure the aforementioned sealing against the escape of steam or vapors during ordinary operation, but which construction will, nevertheless, permit the doors to open under the extreme 110 conditions created, for example, by an explosion.

65 This construction includes the use of a spring member, the inner end of which is secured to the frame of the stove. The outer end 108 of the spring member is so curved 125 that the door may be forced open and will be retained in a fairly tight manner by the spring member. A handle 104 is pivoted to 130

the frame, at the point 105, so that when the handle is turned into a horizontal position, the inner end will bear against the spring member in such a manner as to further compress the door into the closed position. This fact will be readily appreciated also from an examination of Fig. 4. It will be observed from examining Fig. 4 that it is possible to drive the door open by the exertion of an abnormal pressure on the interior, because in such case the inner end 103 of the spring will yield to permit the accomplishment of this result.

It is very desirable to be able to observe the condition of the flame of the burner without having to open the door 78. I have, therefore, provided the construction which I will now describe, for permitting the accomplishment of this result. Through the central portion of the door 78 there extends an opening indicated by the numeral 107 in Fig. 2. This opening is closed by a plate of glass or mica, or other suitable transparent material 108. The inner side of the opening 107 is closed by a pair of sheets of mica or the like, 109 and 110, which are separated a slight distance by a peripheral ring 111. A mirror 112 is seated in the bottom portion of the opening 107, said mirror being so placed that the operator, by looking down through the window 108 from the normal position of observation, will observe the reflection of the flame and burner in the mirror without having to stoop or assume an inconvenient position. The use of the double sheet comprising the plates 109 and 110, separated by the spacer 111, will largely, if not entirely, eliminate the condensation of water vapors and the like on the mirror 112, as well as the window 108 and the sheets 109 and 110, so that the condition of the burner and flame can be observed at all times in a clear and distinct manner. When desired, a thermometer 113 may be introduced into the door 18 for the purpose of indicating the exact temperature existing on the interior of the closed oven.

The heat insulating spaces may be filled with any desired material, such as kieselguhr, powdered pumice, cork, asbestos, or any other suitable material. However, when such finely powdered materials as kieselguhr are used, they will be thoroughly and efficiently retained within the heat insulating spaces by reason of the efficient manner in which the various co-operating

sheets are brought together. Manifestly, the sheets may be soldered or bolted or welded at any points desired, but ordinarily this will be unnecessary, because of the manner in which the various sheets are set together.

While I have herein shown and described only a single embodiment of the features of my invention, still it will be understood that I do not in any manner limit myself to the said embodiment, except as I may do so in the claims.

I claim:

1. In a stove adapted for the use of fuels giving products of combustion either heavier or lighter than air, the combination with a closed oven of a combustion chamber beneath the same, a burner in said combustion chamber, passages for delivering air through the sides of said chamber to the burner, heating passages leading upwardly from said chamber along the sides of the oven to a point above the bottom of the oven, discharge passages leading downwardly from said passages along the sides of the oven and the combustion chamber to a discharge connection at the bottom of the stove, other discharge passages leading away from the upper ends of the heating passages, and means for closing the last mentioned passages for the purpose of directing all the products of combustion downwardly and out of the heating passages, substantially as described. 90

2. In a stove adapted for the use of fuels giving products of combustion either heavier or lighter than air, the combination with an oven of a combustion chamber beneath the same, a burner in said combustion chamber, there being openings for the delivery of air into said combustion chamber to the burner, heating passages leading upwardly from the combustion chamber along the sides of the oven to a point above the bottom of the oven, discharge passages leading downwardly along the sides of the oven and the combustion chamber to a point of discharge below the burner, other discharge passages leading away from the upper portions of the heating passages, and means for controlling the flow of gases out of the heating passages by either set of discharge passages as desired, substantially as described. 105

STEPHEN S. THOMAS.
